UNITED STATES PATENT OFFICE.

MORRIS BERNHARD, OF NEW YORK, N. Y., ASSIGNOR TO DREYFUS BROTHERS, OF SAME PLACE.

DESIGN FOR A PENDANT.

SPECIFICATION forming part of Design No. 15,737, dated January 20, 1885.

Application filed November 18, 1884. Term of patent 7 years.

To all whom it may concern:

Be it known that I, MORRIS BERNHARD, of the city, county, and State of New York, have produced a new and original Design for Pendants, of which the following is a specification.

Reference is to be had to the accompanying drawing, forming a part of this specification, in which a face view of my new design for pendants is shown.

10 A is a ball tuft or slung ruff. C is a cord depending from the said ball tuft or ruff; B, a disk on the lower end of the cord C. F is a cord depending from the disk B, and E is a ball or tuft on the lower end of the cord F. 15 G is a bead on the face of the disk, and H are radial cords on the same, extending from the bead to the rim of the disk. J is a furry border on the periphery of the disk B, and K is a loop on the tuft or ball A.

20 I claim—

1. The herein-described design for pendants, consisting of a ball or tuft, a disk depending from the ball, and a ball or tuft depending from the disk, substantially as set forth.

2. The herein-described design for pendants, 25 consisting of a ball or tuft, a disk depending from the ball, a bead on the disk, and radial cords extending from the bead to the rim of the disk, substantially as set forth.

3. The herein-described design for pendants, 30 consisting of a ball or tuft, a disk depending from the ball, radial cords on the disk, and a furry border on the rim of the disk, substantially as herein set forth.

4. The herein-described design for pendants, 35 consisting of the ball or tuft A, the disk B, depending from the same, the ball or tuft E, depending from the disk, the bead G, the cords H on the disk, and the furry border J on the rim of the disk, substantially as herein shown 40 and described.

MORRIS BERNHARD.
